UNITED STATES PATENT OFFICE

THEODOR R. WILLWERSCHEID, OF ST. PAUL, MINNESOTA

LAMP-POST WITH ILLUMINATED STREET SIGNS

Application filed May 25, 1925. Serial No. 32,619.

The present invention relates to a combined street light and illuminated sign.

It is common practice in the art of street lighting, to have positioned below the lamp portion of a lighting device, a plurality of plates, which are usually of embossed sheet metal, bearing thereon the names of the streets at the intersection of which the lighting device is positioned.

10 While street signs placed in this manner are readily visible by day, it is difficult to read the signs at night, owing to the fact that the glare from the light blinds the eyes of a person attempting to read them.

15 An object of the present invention is to position a transparency containing a sign adjacent an illuminating means to cause a portion of the rays from the illuminating means to be diverted, by means of a reflector, to illuminate the transparency.

Another object is to position a reflector adjacent an illuminating means in a street lamp to direct a portion of the light rays therefrom through a transparency having indicia 25 thereon.

Another object is to position a transparency having indicia thereon with respect to an illuminating means to be illuminated by a device acting in connection with the illuminating means.

In order to attain these objects there is provided, in accordance with one feature of the invention, an illuminating means, such as an electric lamp, positioned within a transparent housing to depend from the upper portion thereof. Below the transparent housing is positioned a secondary housing having a plurality of transparencies set in the sides thereof. Positioned centrally of the secondary housing to lie below the first housing is a conical reflector, the sides thereof being angularly disposed to deflect a portion of the light rays coming from the illuminating means outwardly through the transparencies 45 to illuminate them.

These and other features of the invention, not specifically mentioned will be more fully brought out in the following description and the accompanying drawings, wherein:

60 Figure 1, is a view partly in side elevation

and partly in vertical section, of a street lamp made in accordance with the present invention.

Figure 2 is a sectional view on the line 2—2 of Figure 1.

Figure 3, is a view in plan and side elevation, respectively, of a supporting spider; and

Figure 4, is a view in elevation of a modified form of the device, a portion thereof being broken away to show the interior structure thereof.

Referring to the drawings in detail, the invention is shown embodied in a street lamp of a well known type, wherein a supporting post A is composed of a plurality of cast metal elements, comprising a column 1, an enlarged member 2 seated in a groove on the top of the column 1, and a cap portion 3 seated in turn on top of the member 2. The parts are 65 firmly locked in superposed relation by means of tie rods 4 firmly embedded in the base of the lamp post and engaging a metal spider 5, the arms 6 of which overlap the inner edge of the cap member 3 and firmly bind the parts 70 together when nuts 7, threadedly engaging the upper end of the tie rods, are screwed down to draw the spider downward into intimate engagement with the cap member 3.

Firmly affixed to the cap member, as by 80 means of screws 8, are four brackets 9 positioned to extend radially beyond the cap member to form a supporting frame for a lamp structure B mounted thereon. Affixed to the upper portion of the brackets 9, to be 85 supported thereon, is an annular member or spider 10 having inwardly projecting lugs 11 integral therewith, each of the lugs having a hole drilled therein.

The upper surface of the frame formed 90 by the brackets 9 is preferably covered by a sheet of metal 12, of square plan view and having the configuration illustrated in Figure 1. The sheet 12 may be secured to the brackets as by means of screws 13, the central portion of the sheet 12 extending inwardly over the spider 10 and having a central opening to correspond with the central opening of the spider. Each of the outer edges of the plate 12 is bent to have a channel 14 95

therein, into which may be slidably inserted a transparency 15, which preferably comprises a sheet of transparent or translucent material, such as a heavy sheet of celluloid, having thereon indicia which may comprise the name of a street. The open ends of the channel portion may be closed by a small sheet metal member 16 affixed to each of the brackets 9, as by means of screws 17, to retain the transparent sheets in the channels as shown in Figure 2. A second sheet of metal 18 of square plan view and having a configuration to conform to the lower sides of the brackets 9, is affixed in position by means of screws 19 to cover the lower portion of the frame formed by the four brackets. This second sheet 18 is also provided with a channeled outer edge similar to plate 12 to slidably receive the transparency 15.

20 A plurality of upright ribs 20 are supported on the spider 10 by means of bolts 21 which penetrate the base portion of each of the ribs 20 and extend through a perforation in a lug 11 of the spider to firmly affix the ribs in position. The upper ends of the ribs are firmly affixed to a ring 22 which, in a lamp of the type illustrated, would be octagonal in shape. Each of the ribs is secured to the ring 22 as by means of screws, not shown. Intermediate the ribs 20 to be supported thereby are plates 32 of glass to form a housing about the lamp 28. A cover 23 may be of metal, such as copper, and is here shown as a low octagonal pyramid. A decorative cap 24 may be secured to the top of the cover, as by means of a screw 25.

Extending diametrically of the lamp housing B between two opposite ribs 20 is a lamp support 26 which may comprise a strip of metal. Affixed centrally thereof to depend therefrom is a lamp bracket 27 into which may be inserted, in a well known manner, an incandescent lamp 28. Conductors 29 for the lamp may be carried along the lamp support 26 downwardly along one of the ribs 20 and thence downwardly through the column A.

Secured to the interior of the frame formed by the brackets 9, as by means of screws 30, is a conical reflector 31 which may be of sheet metal, the upper surface thereof being polished or enameled to act as a reflector to divert a portion of the downwardly directed rays from the lamp 28 outwardly through the transparencies 15.

A modified form of the device is shown in Figure 4. In this structure the light housing and supporting post therefor are similar to that shown in Figures 1 and 2. In this modified form however, an auxiliary lamp 32 is mounted upon a bracket 33 supported upon the spider 5, and is firmly held in position thereon by means of the tie-rods 4. The auxiliary lamp 32 is preferably connected in parallel with lamp 34, but is considerably smaller

than lamp 34 so as to consume a minimum amount of electrical current. In the modified form of the device shown in Figure 4, the interior surface of the secondary housing is preferably painted or enameled to reflect the rays coming downward from the lamp 34 to thereby increase the amount of light reaching the transparent signs 15 to illuminate them.

While the embodiments of the invention illustrated show the signs positioned below the light, it is to be understood that such relative positioning of the lights and the transparencies is not essential to the invention, and that any positioning of the transparencies to receive light rays as herein described would come within the spirit and scope of the invention as defined in the appended claims.

What I claim is:

1. A lighting device of the character described, comprising a base, a plurality of radially diverging brackets connected thereto, a sheet metal covering above and below said brackets provided with channels in the outer edges thereof, transparent sign means inserted in said channels to have the edges gripped thereby, a support member connected to the upper portion of said brackets and having an opening therein, a transparent housing mounted on said support member, illuminating means mounted in said housing to direct a portion of the rays from the illuminating means through the opening in the support member, and convex deflecting means mounted below the opening in the support member to deflect illuminating rays passing through the opening in the support member radially outward through the transparency.

2. A combined street lamp and illuminated sign, comprising a sign supporting housing provided with a restricted opening in its top wall, a lamp housing supported by said sign housing and having transparent walls converging toward said restricted opening, a cone-shaped light reflecting means in said sign housing mounted with its apex toward and extending through said opening and into the lamp housing, transparent plates in said sign supporting housing having indicia thereon, and illuminating means carried by said lamp housing and spaced from the apex of said cone-shaped reflecting means, so as to illuminate the lamp housing and have a portion of its rays reflected into the sign housing to illuminate the latter.

3. A combined street lamp and illuminated sign, comprising a base forming a sign housing, said housing having a top wall provided with an opening, transparent plates in said sign housing having indicia thereon, a lamp housing having transparent walls converging toward said opening and supported by the top wall of the sign housing defining said opening, illuminating means disposed in said lamp housing, and a cone-shaped reflector

supported by and extending entirely through
said sign housing and having its apex di-
rected toward and into said opening, said
reflector being spaced from the illuminating
means so as to reflect a portion of the rays of
the latter downwardly through said opening
and into the sign housing to illuminate the
latter.

In testimony whereof I affix my signature.

THEODOR R. WILLWERSCHEID.
